UNITED STATES PATENT OFFICE.

STACY B. HASELTINE, OF CHICAGO, ILLINOIS, ASSIGNOR, BY MESNE ASSIGNMENTS,
TO W. H. MINER, INC., A CORPORATION OF DELAWARE.

COUNTERBALANCED SIDE BEARING.

Application filed July 21, 1923. Serial No. 652,903.

- This invention relates to counter-balanced side bearings.
- One object of the invention is to provide an anti-friction side bearing, especially 5 adapted for railway cars, wherein are employed a minimum number of parts, so constructed that the anti-friction element proper will be returned to central position solely under the influence of gravity.
- 10 Another object of the invention is to provide an anti-friction bearing of the type indicated, wherein are provided means for positively maintaining a predetermined relation between the anti-friction element and 15 retaining member, in all positions of the anti-friction element.
- A further object of the invention is to provide an anti-friction bearing of the type indicated wherein the anti-friction element is 20 so shaped that it has contact with the housing walls in substantially all positions thereof, thereby preventing the entrance of foreign matter into the housing beneath the anti-friction element.
- 25 Other objects and advantages of the invention will more clearly appear from the description and claims hereinafter following.
- In the drawing, forming a part of this 30 specification, Fig. 1 is a vertical, sectional view taken through the end of a car body bolster and truck bolster, showing my improvements in connection therewith. Fig. 2 is a top plan view of the anti-friction 35 bearing proper shown in Fig. 1. And Fig. 3 is a vertical, sectional view taken substantially on the line 3—3 of Fig. 1.
- In said drawing, 10 denotes the under side 40 of a car body bolster and 11 the upper side of an opposed truck bolster. I have shown my improved bearing as secured to the truck bolster. The bearing comprises, broadly, a retainer member or base casting A and an anti-friction element B.
- 45 The retainer member or base casting is in the form of an arched housing, open at the top and bottom, having parallel spaced side walls 12—12 and upwardly and inwardly curved end walls 13—13, the side walls being provided with continuous lateral flanges 14 along the edges thereof, projecting inwardly at right angles therefrom and forming a continuation of the end walls 13, defining an opening 15 through which the upper portion of the anti-friction element is adapted to project. The opposite end portions of the flanges 14, adjacent the walls 13, are upwardly and inwardly curved similarly to the end walls 13, and the inner surfaces thereof form continuations of the 55 curved inner bearing surfaces of the walls 13. The upper, longitudinally extending portion 17 of the flanges which connect the end portions 16 are also slightly curved upwardly, as clearly shown in Fig. 1. At the lower edges, the side walls are provided with longitudinally extending, outwardly projecting flanges 18 having corner lugs 19, perforated to accommodate rivets or other suitable securing means for attaching the member A to the bolster. To promote the life of the bearing, I preferably provide a transversely extending steel plate 20, which also serves as a shelf to support the anti-friction element above the upper surface of the truck bolster, the flanges 18 of the housing being centrally off-set to provide transversely extending, downwardly opening, aligned channels 21—21 adapted to accommodate the opposite end portions of the plate 20, the latter being rigidly secured to the housing A by rivets fastened through the off-set portions of the flanges 18.
- 60 As clearly indicated in Fig. 1, the shelf or plate 20 is disposed centrally lengthwise of the member A with a considerable clearance between each edge of the plate and the inner face of the adjacent end wall 13. Furthermore, the combined shelf and plate 20 is so formed as to present the upper face or bearing surface at a considerable elevation 65 above the bottom proper of the member A and the upper surface of the truck bolster. To facilitate the clearing out of dirt or other foreign matter which may accumulate within the housing A, the end walls thereof may be cut away as indicated at 22.
- 70 The anti-friction element B, as shown, is in the form of a rocker of a width approximating the inside width of the housing A, and of such a length that the opposite ends thereof engage the opposite end walls 75 of the housing when the rocker is in normal position, as shown in Fig. 1. The element B

has an upwardly extending bearing projection 23 centrally disposed longitudinally thereof and extending through the opening 15 of the housing A and adapted to co-act 15 with the under surface of the body bolster 10. As clearly shown in Figs. 1, 2 and 3, the bearing projection 23 is of a width closely approaching the width of the opening 15. The opposite ends of the element B, at the 10 lower side thereof, are provided with downwardly extending projections 24 each having a flat lower end face 25 adapted to abut the flat upper face of the truck bolster when the rocker is moved to one of its extreme 15 positions, each projection being of such a width that it may freely enter the corresponding space between the plate 20 and the corresponding end wall 13 of the housing. Between the projections 24, the element B is 20 provided with a longitudinally extending, lower, curved bearing surface 26 adapted to co-act with the plate 20, thereby supporting the element B for rocking movement. The element B is also provided with a pair of 25 symmetrically arranged, upwardly and inwardly curved, upper guide surfaces 27 adapted to co-act respectively with the end walls 13 of the housing. The opposed end portions of the rocker are rounded off as 30 indicated at 28 and the relative position and arrangement of the rounded ends 28, curved guiding surfaces 27 and the lower bearing surfaces 26 are such that the opposite rounded ends 28 of the rocker will be in very light 35 or slight contact with the inner curved surfaces of the end walls 13 during the greater portion of the movement of the rocker and the surfaces 27 will co-act with the flanges 14 and the respective end walls 13 of the 40 housing to limit the rocking movement of the rocker. As the opposite ends 28 of the rocker are in substantially constant but very light contact with the end walls 13 and as the flange 14 overhangs the sides of the main 45 portion of the rocker and the rocker closely conforms in width to the housing, it will be evident that the entrance of dirt, cinders and other foreign material through the top of the housing is substantially prevented, 50 thus minimizing the accumulation of dirt and grit under the rocker and protecting the bearing surfaces of the latter and the plate 20.

The projection 23 is provided with an 55 upper curved bearing surface 29 having the central portion thereof of a curvature of relatively short radius and the opposite end portions of a curvature of relatively long radius, so proportioned and arranged that 60 the upper surface 29 will roll on the under side of the body bolster when the lower surface 26 rocks on the plate, without raising of the body bolster with reference to the truck bolster. In other words, the contacting portions 65 of the upper and lower bearing sur-

faces of the rocker always lie in parallel planes which remain the same distance apart.

The normal position of the parts is that shown by the full lines in Fig. 1, in which 70 position it is evident that the anti-friction element B is slightly spaced from the body bolster. When the bearing is brought into action by a relative radial and approaching movement of the body and truck bolsters 75 and the anti-friction element is rocked to either side of the center or normal position thereof to the position indicated by the dotted lines in Fig. 1, it is evident that the end portions 28 of the rocker will be in continuous but light contact with the end walls 13 of the housing, thereby serving the dual function of guiding the rocker and preventing entrance of foreign material into the 80 housing between the end walls and the ends 85 of the rocker. It will also be evident that, due to the constant but light contact between the opposed ends of the rocker and the curved end walls of the housing, the same relation will always be maintained between 90 the rocker and the housing A, thereby assuring the return of the rocker to central normal position after each actuation.

The limit of movement of the anti-friction rocker B is obtained when one of the surfaces 27 engages against the inner curved surface of the corresponding end wall 14 and the lower abutment surface 25 of the corresponding projection 24 abuts the upper 95 surface of the truck bolster. When the pressure on the bearings is removed, the anti-friction element B will return to normal position under the influence of gravity, guided in its rocking movement on the plate 20 by engagement between the opposed ends 100 28 of the rocker and the walls 13 of the 105 housing.

In the drawing, while I have shown both ends of the rocker as simultaneously engaging both end walls of the housing or retaining member, nevertheless, it will be understood that the contact is extremely light or slight and, in actual practice, there will be preferably, a slight clearance permissible, at least between one end of the rocker and housing, depending upon the possible slight shifting of the anti-friction element. This 110 will be done in order to prevent binding of the parts and to assure proper return of the anti-friction element to its central normal position, when released, under the influence of gravity. It will also, of course, be understood by those skilled in the art that the curvature of the end walls 13 of the retaining member will be made such as to correspond 115 to the lines generated by those portions of the anti-friction element which are adapted to engage the inner surfaces of said end walls 13.

I have herein shown and described what 120 125 130

I now consider the preferred manner of carrying out the invention, but the same is merely illustrative and I contemplate all changes and modifications that come within 5 the scope of the claims appended hereto.

I claim:

1. In an anti-friction bearing, the combination with a housing having side and end walls; of an anti-friction rocker within the 10 housing shaped and adapted to always closely approach all of said walls in all positions of the rocker to substantially prevent the entrance of any foreign material from above the anti-friction rocker to a point below it.
2. In an anti-friction bearing, the combination with a housing open at the top and having end walls spaced longitudinally of the housing; of an anti-friction rocker 20 movable longitudinally within the ends of the housing, said rocker being provided with rounded ends adapted to simultaneously engage both ends of the housing throughout the movement of the rocker and having 25 a bearing projection thereon extending through and above said opening.
3. In an anti-friction bearing, the combination with an arched housing having upwardly and inwardly curved end walls; of an elongated gravity centering rocker disposed within said housing, said rocker being of a width approximating the width of the housing and having its opposite ends in 30 substantially constant but light engagement with the opposite end walls of said housing.
4. In an anti-friction bearing, the combination with an arched housing having upwardly and inwardly curved end walls; of an elongated rocker disposed within said 40 housing, said rocker being of a width approximating the width of the housing and having its opposite ends adapted for light engagement with the opposite end walls of

said housing, said housing being provided with inwardly extending flanges adapted to 45 overhang the opposite sides of the rocker and retain the same within the housing.

5. In an anti-friction bearing, the combination with an arched housing having upwardly and inwardly curved end walls; of an elongated rocker disposed within said housing, said rocker being of a width approximating the width of the housing and having its opposite ends adapted for light engagement with the opposite end walls of 55 said housing, said housing being provided with inwardly extending flanges adapted to over-hang the opposite sides of the rocker and retain the same within the housing; and a wear plate secured to said housing and 60 adapted to support said rocker.

6. In a side bearing, adapted to be secured to a truck bolster and co-acting with the opposed body bolster of a car, the combination with a housing having side and end walls, said side walls being provided with inwardly extending flanges; of an anti-friction element within the housing, said element having an upper bearing portion extending beyond said flanges and adapted 70 to co-act with the body bolster, said element being elongated and having its opposite ends adapted for light engagement with the opposite end walls of said housing; a plate secured with the said housing and 75 adapted to support the anti-friction element spaced above the upper surface of the truck bolster, said element having means thereon adapted to engage the end walls and flanges of the housing and the upper surface of 80 the truck bolster to limit its rocking movement.

In witness that I claim the foregoing I have hereunto subscribed my name this 19th day of July 1923.

STACY B. HASELTINE.
